OIL COOLER

Alessandro Tebald, Milan, Italy

Application October 10, 1932, Serial No. 637,184
In Germany October 22, 1931

17 Claims. (Cl. 257—247)

In connection with radiators for cooling oil and particularly lubricating oil for aircraft engines and generally for machines and engines, it is known to use by-pass valves loaded by a suitable spring and interconnecting the radiator inlet and outlet ducts, such by-pass valves being intended to provide for a direct flow of oil to the engine or the like when oil is cold and there is therefore too much resistance against its flow through the radiator.

Such provision is defective in that when the radiator is very cold and oil within it is very viscous, the whole amount of oil conveyed by the oil circulating pump discharges through said by-pass valve and such flow through the by-pass valve tends to continue even when the oil has reached a very high temperature, because the hot oil does not pass through the radiator which remains cold owing to the action of the cooling fluid thereon, the flow of liquid through it being thus permanently restricted.

The present invention has for its object a radiator in which the drawback above referred to is removed in that a by-pass valve is provided in the radiator at the outlet thereof, so that the oil must flow through at least a portion of the radiator. Therefore the hot oil flowing through the radiator heats the same radiator and the oil enclosed therein and makes such oil fluid thus assisting progressively the normal circulation of oil through the radiator.

The present invention comprises further an arrangement providing for an oil circulation through the radiator which progressively increases with the decrease of resistance against such circulation.

An embodiment of this invention is shown by way of example on the annexed drawings and

Figure 1 is a longitudinal section of a radiator on line 1—1 of Fig. 5, with portions removed;

Figure 2 is a view of the internal member of the radiator, said view being developed in a plane and extending through arc 2—2 of Figure 5;

Figure 3 is a section on line 3—3 of Figure 6; Figure 4 is a fragmentary section on line 4—4 of Fig. 6;

Figure 5 is in its top half a section on line 5—5 of Fig. 3 and in its bottom half a section on line 5'—5' of Fig. 1;

Figure 6 is a section on line 6—6 of Figures 1 and 3.

As shown on the drawings, the radiator of this invention comprises an internal tubular member 1 having a flange 3 at one end and

having heat radiating fins 2 in its internal surface, a number of such fins being omitted in Fig. 1. A sleeve 4 having outer heat radiating fins 5 is inserted over member 1 and is held in position by means of a screw-threaded collar 6 60 which is screwed on the end of member 1 opposed to its end flange 3 said collar acting to force sleeve 4 against a ring 7 encircling the member 1 and abutting its flange 3. The joints intermediate the described parts are sealed by 65 packing members 8, 9, 10, and 11.

The path for oil circulation through the radiator is provided by grooves 12, 12', 12'' cut in the outer surface of member 1 and leaving intermediate longitudinal ribs 13, 13' which connect alternately with annular end ribs 14, 14' and leave end passages 15, 15' interconnecting the adjacent grooves 12, 12' and 12'' as shown in Fig. 2.

At one of their ends member 1 and sleeve 4 75 provide a circumferential groove 16 into which opens the inlet port 17 (Figures 3 and 5); ducts 18, 18 having a larger sectional area than grooves 12, 12' originate from said groove 16 and communicate at their opposed ends with passages 80 15' between adjacent grooves 12, said ducts 18, 18 being closed at last named ends by annular rib 14'. Flange 3, ring 7 and portions of the wall of the outer sleeve 4 form an annular collecting duct 19 lying at the radiator end opposed to that 85 where the inlet port 17 is provided, said duct 19 leading to an outlet port 20 provided in ring 7. Duct 19 is divided from grooves 12, 12' and ducts 18, 18 by a partition 4' extending from sleeve 4, and a ring 21 located as an extension 90 of partition 4' between partition 4' and the annular rib 14'.

The illustrated embodiment comprises two main ducts 18, 18, but of course they may be provided in any desired number on the outer 95 surface of member 1, their total cross sectional area being in any case adapted to permit the flow of the maximum amount of oil which is required to pass through the radiator.

At equal distances from each pair of ducts 100 18, 18 the final grooves 12'' of the path for liquid open directly into the main or collecting duct 19, as shown in Fig. 2.

In each of passages 15', which lie at one end of passages 18, 12' and 12 is a port opening 105 through the ring 21 into the duct 19. Each port 22, 22', 22'' is provided with a shutter 23, 23', 23'' which is carried by a strip or blade member 24 fastened on ring 21, and all said shutters close their cooperating ports 22, 22', 22'' under 110

the action of a resilient loading member as hereinafter described.

- In the illustrated embodiment said resilient loading means directed to close shutters 23, 23', 23'' include a wire 25 which bears on said shutters, the ends of said wire passing under pulleys 27 and being engaged by means of an adjusting screw plug 29 in a perforated plunger 28 loose within outlet passage 20. Said plunger 28 is under the action of a spring 30 which abuts on the flange 31 of passage 20 and acts to draw the ends of wire 25 outwardly and to force said wire radially on shutters 23, 23', 23'' thus forcing them against their respective ports 22, 22', 22''.

Ports 22, 22', 22'' have different sizes and shutters 23, 23', and 23'' on which the wire 25 bears, extend different distances radially from the axis X—X, there being antifriction members 33 between the shutters and wire; thus the tension of wire 25 produces different radial actions on said shutters such actions being larger in respect of shutters which are of greater thickness and whose point of contact with wire 25 is therefore more spaced from radiator longitudinal axis X—X while they are reduced in respect of shutters having less thickness.

Ports 22, 22' and 22'' between the duct 18 and the discharge groove 12'' are of progressively increasing size, port 22 at the end of duct 18 being the smallest, and port 22'' adjacent groove 12'' being the largest. The shutter 23 for the small port 22 is thicker, that is, it projects a greater distance from the axis X—X than the shutter 23' for port 22' and the shutter 23'' for port 22'' projects less than shutter 23''. Therefore, the wire 25 presses the shutter 23'' less firmly against its port 22'' than the shutters 23' and 23 are pressed against the ports 22' and 22. The largest port 22'' will therefore be opened by a smaller oil pressure than ports 22' and 22. As the pressure increases, ports 22' and 22 will be opened.

In operation, when the radiator has reached its normal temperature of operation, the oil conveyed thereto by a pump (not shown) through inlet passage 17, enters annular groove 16 and thereafter it flows to main duct 19 through ducts 18 and grooves 12, 12' and 12'' of each set, the back pressure of oil under these conditions being low due to fluidity of oil when hot; therefore under these conditions shutters 23, 23', 23'' are closed under loading action of wire 25 and spring 30, and the oil flows through the respective passages 18, 12, 12', and 12'' and discharges into main 19.

When the temperature of radiator and oil decreases the oil viscosity increases and then the back pressure within radiator increases, this fact causing shutters 23'', 23', 23 to open after each other, starting from those having a larger area and subject to a lower pressure by wire 25 and spring 30; therefore shutters 23'' are caused to open and oil flows to main 19 through ports 22'' without flowing through subsequent grooves 12, and 12''. When the temperature decreases further and back pressure increases, shutters 23' and finally shutters 23 are caused to open; then oil flows from inlet port 17 directly to main 19 and to outlet 20 through ducts 18, 18.

Thus the radiator body is permanently heated by hot oil flowing always through a portion

(ducts 18) of it even when the radiator is substantially inoperative.

On the contrary, when the temperature is rising in the radiator, the viscosity and back pressure of oil are dropping and then shutters 23, 23', and 23'' close in succession, the oil being caused to flow through the full cooling path provided by grooves 12, 12', 12''.

In any case hot oil is at any time caused to flow through at least a portion of the radiator and thus such radiator never is entirely cut off from the path of hot oil said oil flowing always through ducts 18, 18; therefore said oil progressively heats adjacent grooves 12 . . . and tends to maintain the radiator in condition for its normal operation.

What I claim as my invention and desire to secure by United States Letters Patent is:—

1. A radiator for cooling viscous liquids comprising a radiator body having an inlet and an outlet, a passage communicating with said outlet, means in said body providing a duct leading from said inlet to said outlet passage, a by-pass valve at the outlet passage end of said duct, means providing a path for fluid to be cooled in radiator body and leading from the outlet passage end of said duct to said outlet passage, said path comprising a number of sections each having a port opening into said outlet passage, by-pass valves each controlling one of said path ports and means tending to hold said by-pass valves closed, said by-pass valves being adjusted to open in progression beginning from the most remote one from said duct on an increase of back-pressure occurring within said radiator body.

2. A radiator for cooling viscous liquids comprising a radiator body having an inlet and an outlet, a passage communicating with said outlet, means in said body providing a duct leading from said inlet to said outlet passage, a by-pass valve at the outlet passage end of said duct, means providing a path for fluid to be cooled in said radiator body and leading from the outlet passage end of said duct to said outlet passage, said path comprising a number of sections each having a port opening into said outlet passage, by-pass valves each controlling one of said path ports and means tending to hold said by-pass valves closed, said by-pass valves having different areas subject to back-pressure within said radiator to open and close in progression under varying back-pressures within said radiator body.

3. A radiator for cooling viscous liquids comprising a radiator body having an inlet and an outlet, a passage communicating with said outlet, means in said body providing a duct leading from said inlet to said outlet passage, a by-pass valve at the outlet passage end of said duct, means providing a path for fluid to be cooled in said radiator body and leading from the outlet passage end of said duct to said outlet passage, said path comprising a number of sections each having a port opening into said outlet passage, by-pass valves each controlling one of said path ports and means tending to hold said by-pass valves closed, said by-pass valves having increasing areas subject to back-pressure within said radiator beginning from the outlet passage end of said duct to open in succession beginning from the most remote one from the outlet passage end of said duct on an increase of back-pressure within said radiator body.

crease of back-pressure occurring within said radiator.

11. A radiator for cooling viscous liquids comprising a radiator body consisting of two concentric sleeves having annular grooves at their ends provided with an inlet and an outlet respectively, the contacting surfaces of said sleeves being recessed to provide a duct leading from said annular inlet groove and having a port opening in said annular outlet groove and a number of adjacent longitudinal grooves connected with each other at their alternate opposed ends, the first one of said adjacent longitudinal grooves being connected with the annular outlet groove end of said duct and the last one opening into said annular outlet groove, the intermediate ones of said adjacent longitudinal grooves having ports leading to said annular outlet groove at a number of their interconnection points, by-pass valves each controlling one of said ports and loading means for said by-pass valves, said by-pass valves being adjusted to open in progression beginning from the most remote one from said duct on an increase of back-pressure occurring within said radiator.

12. A radiator for cooling viscous liquids comprising a cylindrical radiator body providing an inlet and an outlet, an annular passage communicating with said outlet, means in said body providing a duct leading from said inlet to said outlet passage, a by-pass valve at the outlet passage end of said duct, means in said radiator body providing a number of adjacent grooves connected with each other at their alternate opposed ends, the first one of said grooves being connected with the outlet passage end of said duct and the last one opening into said outlet passage, the intermediate ones of said grooves having ports leading to said outlet passage at a number of their interconnection points, by-pass valves each controlling one of said ports, a wire embracing said by-pass valves and spring means tensioning said wire to load said by-pass valves, said by-pass valves being adjusted to open in progression beginning from the most remote one from said duct on an increase of back-pressure occurring within said radiator.

13. A radiator for cooling viscous liquids comprising a cylindrical radiator body providing an inlet and an outlet, an annular passage communicating with said outlet, means in said body providing a duct leading from said inlet to said outlet passage, a by-pass valve at the outlet passage end of said duct, means in said radiator body providing a number of adjacent grooves connected with each other at their alternate opposed ends, the first one of said grooves being connected with the outlet passage end of said duct and the last one opening into said outlet passage, the intermediate ones of said grooves having ports leading to said outlet passage at a number of their interconnection points, by-pass valves each controlling one of said ports, a wire embracing said by-pass valves and adjustable spring means tensioning said wire to load said by-pass valves, said by-pass valves being adjusted to open in progression beginning from the most remote one from said duct on an increase of back-pressure occurring within said radiator.

14. A radiator for cooling viscous liquids comprising a cylindrical radiator body providing an inlet and an outlet, an annular passage communicating with said outlet, means in said body

providing a duct leading from said inlet to said outlet passage, a by-pass valve at the outlet passage end of said duct, means in said radiator body providing a number of adjacent grooves connected with each other at their alternate opposed ends, the first one of said grooves being connected with the outlet passage end of said duct and the last one opening into said outlet passage, the intermediate ones of said grooves having ports leading to said outlet passage at a number of their interconnection points, by-pass valves each controlling one of said ports, said valves having different heights, a wire embracing said valves and spring means tensioning said wire, said by-pass valves being arranged to open in progression beginning from the most remote one from said duct on an increase of back-pressure occurring within said radiator.

15. A radiator for cooling viscous liquids comprising a cylindrical radiator body providing an inlet and an outlet, an annular passage communicating with said outlet, means in said body providing a duct leading from said inlet to said outlet passage, a by-pass valve at the outlet passage end of said duct, means in said radiator body providing a number of adjacent grooves connected with each other at their alternate opposed ends, the first one of said grooves being connected with the outlet passage end of said duct and the last one opening into said outlet passage, the intermediate ones of said grooves having ports leading to said outlet passage at a number of their interconnection points, by-pass valves each controlling one of said ports, said valves having decreasing heights beginning from that of the by-pass valve of the outlet passage end of said duct, a wire embracing said valves and spring means tensioning said wire, to cause said by-pass valves to open in progression beginning from the most remote one from said duct on an increase of back-pressure occurring within said radiator.

16. A radiator for cooling viscous liquids comprising a cylindrical radiator body providing an inlet and an outlet, an annular passage communicating with said outlet, means in said body providing a duct leading from said inlet to said outlet passage, a by-pass valve at the outlet passage end of said duct, means in said radiator body providing a number of adjacent grooves connected with each other at their alternate opposed ends, the first one of said grooves being connected with the outlet passage end of said duct and the last one opening into said outlet passage, the intermediate ones of said grooves having ports leading to said outlet passage at a number of their interconnection points, by-pass valves each controlling one of said ports said by-pass valves having increasing area subject to back-pressure within said radiator beginning from that of said duct, said valves having decreasing heights beginning from that of the said by-pass valve of said duct, a wire embracing said valves and spring means tensioning said wire, to cause said by-pass valves to open in progression beginning from the most remote one from said duct on an increase of back-pressure occurring within said radiator.

17. A radiator for cooling viscous liquids comprising a radiator body having an inlet and an outlet, a passage communicating with said outlet, means in said body providing a duct leading from said inlet to said outlet passage, a by-pass valve at the outlet passage end of said duct, said valve being adjusted to open under a pre-

determined pressure of the liquid, means providing a path for fluid to be cooled in said radiator body and leading from the outlet passage end of said duct to said outlet passage, said path comprising a number of sections each having a port opening into said outlet passage, by-pass valves each controlling one of said ports and means tending to hold said by-pass valves closed, said valves being adjusted to open under pressures of the liquid less than the opening pressure of said first named by-pass valve located in said duct. 80
